DRAFTING MACHINE THUMB CONTROL UNIT

Francis E. Vaughan, Pasadena, Calif.

Application November 8, 1950, Serial No. 12,912

Term of patent 14 years

(Cl. D52—1)

To all whom it may concern:

Be it known that I, Francis E. Vaughan, a citizen of the United States, residing at Pasadena, in the county of Los Angeles and State of California, have invented a new, original, and ornamental Design for a Drafting Machine Thumb Control Unit, of which the following is a specification, reference being had to the accompanying drawing, forming part thereof.

Fig. 1 is a front perspective view of a drafting machine thumb control unit, showing my new design;

Fig. 2 is a rear elevational view thereof;

Fig. 3 is a top plan view of Figs. 1 and 2; and

Fig. 4 is a sectional view taken in the direction of the lines 4—4 in Fig. 1.

I claim:

The ornamental design for a drafting machine thumb control unit, substantially as shown.

FRANCIS E. VAUGHAN.
